US0D1114122S

(12) **United States Design Patent** (10) **Patent No.:** **US D1,114,122 S**
(45) **Date of Patent:** **** Feb. 17, 2026**

(54) **POWERED WHEELED BOARD**

(71) Applicant: **RAZOR USA LLC**, Cerritos, CA (US)

(72) Inventor: **Joey Chih-Wei Huang**, Temple City, CA (US)

(73) Assignee: **Razor USA LLC**, Cerritos, CA (US)

(**) Term: **15 Years**

(21) Appl. No.: **29/925,047**

(22) Filed: **Jan. 22, 2024**

Related U.S. Application Data

(63) Continuation of application No. 29/825,046, filed on Jan. 28, 2022, now Pat. No. Des. 1,012,217, which is a continuation of application No. 29/770,817, filed on Feb. 17, 2021, now Pat. No. Des. 942,572, which is a continuation of application No. 29/717,684, filed on Dec. 18, 2019, now Pat. No. Des. 911,476, which is a continuation of application No. 29/664,559, filed on Sep. 26, 2018, now Pat. No. Des. 871,532, which is a continuation of application No. 29/633,000, filed on Jan. 11, 2018, now Pat. No. Des. 829,838, which is a continuation of application No. 29/576,467, filed on Sep. 2, 2016, now abandoned.
